UNITED STATES PATENT OFFICE.

HERBERT V. LEAHY, OF LOS ANGELES, CALIFORNIA, ASSIGNOR TO HERCULES CARBURETOR COMPANY, OF LOS ANGELES, CALIFORNIA, A CORPORATION OF CALIFORNIA.

CARBURETOR.

1,421,790.

Specification of Letters Patent.

Patented July 4, 1922.

Application filed April 14, 1919. Serial No. 289,981.

To all whom it may concern:

Be it known that I, HERBERT V. LEAHY, a citizen of the United States, residing at Los Angeles, in the county of Los Angeles and

5 State of California, have invented a new and useful Carburetor, of which the following is a specification.

An object of this invention is to produce an intimate mixture of air and liquid fuel 10 for use in internal combustion engines.

Another object is to produce a mixture of substantially the correct proportions of fuel and air at various degrees of throttle opening.

15 Another object is to provide a construction which will break up the fuel into a maximum number of minute particles and distribute said particles uniformly throughout the column of air passing through the carburetor.

Another object is to make provision for using either one of two different fuels, a lighter hydrocarbon and a heavier hydrocarbon.

25 Another object is to provide a construction in which an air valve functions to admit a smaller volume of air to the space adjacent the nozzle orifice at lower engine speeds or power and to admit an auxiliary volume 30 of air to the space adjacent the nozzle at higher engine speeds or power.

Another object is to make provision for spreading the fuel over a face of relatively large area exposed to a moving column of air 35 so that the fuel will be readily absorbed by the air.

Other objects and advantages will appear in the subjoined detailed description.

The accompanying drawings illustrate the 40 invention:

Figure 1 is a side elevation of a carburetor built in accordance with the provisions of this invention.

Fig. 2 is a plan section on line indicated 45 by x^2-x^2 , Figs. 1 and 3.

Fig. 3 is a vertical mid section of the carburetor on a plane at right angles to the direction of sight in looking at Fig. 1.

Fig. 4 is a plan section on the irregular 50 line indicated by x^4-x^4 , Fig. 3.

Fig. 5 is an enlarged fragmental vertical section of that portion of the carburetor on the right in Fig. 3.

Fig. 6 is an inverted plan section on the 55 irregular line indicated by x^6-x^6 , Fig. 5.

Fig. 7 is an inverted plan section on the irregular line indicated by x^7-x^7 , Fig. 5.

Fig. 8 is a plan section on the line indicated by x^8-x^8 , Fig. 3.

Fig. 9 is a perspective view of the air 60 nozzle shown in Figs. 3 and 5.

Fig. 10 is an elevation of the collar.

There is provided a float chamber 1 screw-threaded at its lower end into a base 2 which is provided with a chamber 3 communicating with the chamber 1. The base 2 is connected at one end by a nipple 4 and union 5 with the circular bottom 6 of a tubular mixing chamber indicated in general by the character 7. The bottom 6 is provided 70 with a fuel duct 8 and said fuel duct communicates through the nipple 4 with one end of a duct 9 in the base 2, the other end of said duct 9 communicating through a three-way valve plug 10 with the chamber 3 when said 75 valve plug is in the position shown in Fig. 3. When the valve plug 10 is turned to another position it affords communication between the duct 9 and a duct 11 which communicates with a coupling 12 connected with 80 an elbow 13, said elbow being adapted to form a portion of a pipe line extending to a tank, not shown, containing relatively light fuel as, for example, gasoline.

Screw-threaded into the base 2 is a valve 85 chamber 14 in which is a needle valve 15 to control a port 16 in said valve chamber, said valve chamber communicating with a coupling 17 connected with an elbow 18, the elbow 18 being adapted to form a portion of a 90 pipe line to connect the carburetor to a suitable tank, not shown, containing heavier fuel such as, for instance, distillate or the like. The needle valve 15 is controlled by suitable means to regulate the level of fuel in the float 95 chamber 1 and such means may be constructed as follows: The upper end of the needle valve 15 is adapted to be engaged by one end of a lever 19 pivoted at 20 in the chamber 3 of the base 2, the other end of said lever 100 engaging an eye 21 which is screw-threaded onto the lower end of a stem 22. Surrounding the stem 22 is a float 23 which is prevented from rising relative to the stem 22 by an abutment 24 screw-threaded onto the stem 105 22, the opposite ends of the abutment 24 being guided in vertical ways 25 formed in the inner face of the peripheral wall of the chamber 1, and said ways extending longitudinally of the float chamber 1. Thus the abut- 110

ment 24 is adjustable on the stem 22 so as to regulate the level at which the float 23 will cause closing of the needle valve 15 to shut off the flow of fuel into the chamber 3. The 5 upper end of the stem 22 slides in the bore 26 of a stem guide 27 which is screw-threaded into a hollow boss 27' on the top of the chamber 1. In axial alignment with the upper end of the stem 22 in the bore 26 is a 10 push rod or tickler 28 having at its outer projecting end a head forming an abutment 29, there being a coil spring 30 between the abutment 29 and the guide 27 to tend to normally hold the tickler 28 out of engagement 15 with the stem 22. When the abutment 29 is depressed against the pressure of the spring 30 it causes the tickler 28 to push downwardly on the stem 22 so as to operate the lever 19 to retract said lever from the 20 needle valve 15 and allow said needle valve to be opened by the pressure of fuel in the port 16 so that the fuel will flow through the valve chamber 14 into the chamber 3. By the means just described the operator can 25 cause the level of fuel in the chamber 1 to rise above that predetermined by the float 23.

The bottom 6 is provided with an annular shoulder 31 on which rests an air admission member 32 which is provided in its bottom 30 with a circular opening 33 to fit the bottom 6. The top of the air admission member 32 is provided with a circular opening 34 to fit an annular shoulder 35 on the outside of the mixing chamber 7. The air admission member 32 surrounds the lower portion of the chamber 7. The air admission member is provided at one side with an inlet port 36, and it is clear that the member 32 may be turned relative to the mixing chamber 40 to various positions, the advantage of this being that the port 36 can thus be connected at various angles with a hot air tube, not shown, which may be connected with any suitable heater, not shown, for heating 45 the air entering the air admission member 32. The port 36 is controlled by a butterfly valve 37 which never entirely closes said port, and the air admission member 32 is provided between the valve 37 and outer end 50 of the port 36 with openings 38 controlled by a rotary tubular valve 39 having openings 40 which may be brought into registration with the openings 38 by appropriate turning of the valve 39 to admit 55 atmospheric air directly into the air admission member 32 so as to dilute the heated air entering the port 36. The valve 39 is provided with an operating member 41 and the valve 37 is provided with an operating 60 member 42.

The portion of the mixing chamber 7 positioned inside of the air admission member 32 is provided with ports 43 near the lower end of the mixing chamber. Slidable in the 65 mixing chamber 7 is a suction-operated tubu-

lar air valve 44 which at its lower end forms a sleeve 45 of reduced diameter so as to form an annular passage 46 between the wall of the mixing chamber 7 and the periphery of the sleeve 45 adjacent the ports 43. The 70 sleeve 45 of the air valve substantially fits the outside of an annular flange 47 of a collar 48 which is screw-threaded onto the lower end of a cylinder or tubular fuel chamber 49, that in turn is screw-threaded onto 75 an upwardly projecting boss 50 of the bottom 6. The flange 47 is provided with ports 51 which may be of V-shaped construction so as to be reduced downwardly.

The valve 44 is provided with an inwardly 80 extending annular shoulder 52 adapted to engage an external annular seat 53 on a frusto-conical or upwardly reduced air-discharge nozzle 54. When the shoulder 52 engages the seat 53 it limits downward movement of the valve 44 and when thus engaged the ports 51 in the flange 47 are almost, but not quite, closed by the air valve, as clearly shown in Fig. 3. The air nozzle 54 is provided below the seat 53 with a port or ports 90 55 and said air nozzle is screw-threaded onto an annular flange 56 of a cap 57 which closes the upper end of the fuel chamber 49 and also forms a nozzle base. Thus it is clear that, when the valve 44 is in position to engage the seat 53, air in the interior of the valve 44 can only flow through the ports 55 into the bore of the air nozzle 54 and that, when the valve 44 is raised, the air in the air valve 44 can flow through the ports 55 and 100 also between the valve 44 and air nozzle 54 outside of said air nozzle.

The cap 57 is provided with an opening 58 through which passes a chamber 59 of a valve 60 that is located at the upper end of a 105 duct 8 to control said duct. The chamber 59 is provided with ports 61 to admit fuel from said chamber to the cylinder 49. The lower end of the chamber 59 is screw-threaded into a hollow plunger 62 adapted 110 to work in the cylinder 49, the plunger and cylinder 49 functioning as a dashpot to retard and steady the valve 60 on the opening movement of said valve. The lower end of the chamber 59 is provided with a port or 115 ports 63 to admit fuel from the bore of the plunger 62 to said chamber. The plunger 62 is guided by a cylindrical post 64 through which the duct 8 extends, said post being integral with the bottom 6. Fastened to the upper end of the chamber 59 is a rod 65 which passes through a bridge 66 formed on the upper end of the valve 44, the upper end of the rod being screw-threaded to receive a nut 67. The rod 65 and chamber 59 together form the stem of the valve 60. Screw-threaded on the rod 65 beneath the bridge 66 is a shoulder or collar 68 adapted, when the valve is down, to rest upon the upper end of an upper hollow frusto-conical external noz- 130

zle member 69 which is provided with an internal shoulder 70 screw-threaded on the upper end of an internal tubular nozzle member 71, there being downwardly extending 5 spaced feet 72 on the lower end of the nozzle member 71 adapted to rest on the upper flat face of an intermediate hollow frusto-conical external nozzle member 73 so as to form an annular nozzle discharge orifice 74 between 10 the nozzle members 69, 73. The lower end of the nozzle member 73 is provided with downwardly extending spaced feet 75 adapted to rest on the upper flat face of the cap 57 so as to form an annular nozzle orifice 76 15 between the nozzle member 73 and cap 57. In the drawings the nozzle orifices 74, 76 are exaggerated in size for clearness of illustration and in actual practice said orifices will only be one or two thousandths of an inch 20 in thickness.

The internal nozzle member 71 is provided with ports 77 and the chamber 59 is provided above the level of the cap 57 with a port or ports 78 so that fuel can flow from the chamber 25 59 through the ports 78 into the internal nozzle member 71, thence through the ports 77 into the upper and intermediate external nozzle members 69, 73 and thence through the nozzle orifices 74, 76 to the space between 30 the external nozzle members and the air nozzle 54.

The mixing chamber 7 is provided with an outlet 79 which is controlled by a butterfly valve 80 operated by an arm 81.

35 In practice, the abutment 24 will be adjusted on the stem 22 to a position to allow the fuel to rise to a level preferably somewhat higher than the level of the nozzle orifice 76. Assuming that the inlet 36 is connected with a source of hot air supply, that the outlet 79 is connected with the intake manifold of an internal combustion engine, that the elbow 13 is connected with a source of supply of a heavier hydrocarbon such as 40 45 distillate, that the valve 10 has been turned to position to admit fuel from the fuel supply pipe to the duct 9 and to shut off the duct 9 from the chamber 3, and that the throttle valve 80 and valves 37, 39 are closed 50 55 60 the carburetor operates as follows: The engine is cranked in the usual manner and the comparatively slight suction produced in the air nozzle 54 causes the gasoline to flow from the cylinder 49 through the ports 61 into the chamber 59, thence through the ports 78 into 65 the nozzle member 71, thence through the ports 77 to the bores of the nozzle members 69, 73, and thence through the nozzle orifices to mix with the comparatively small amount 70 of air admitted through the ports 51, the air valve 44 being in the position shown in Fig. 3 so that air will pass from the passage 46 beneath the lower end of the sleeve 45 and thence through the ports 51. The mixture 75 80 85 90 95 100 105 110 115 120 125 130 of air and fuel will flow from the air nozzle 54 into the upper portion of the mixing chamber 7 and thence through the outlet 79 into the intake manifold of the engine where ignition of the charges will take place in a manner well understood in the art pertaining 70 to internal combustion engines. After the engine has run a short time on the mixture of air and gasoline so as to heat the engine, the valve 10 will be turned to the position shown in Fig. 3 so as to admit the lower 75 grade of fuel to the duct 9 and said fuel will pass to the chamber 59 through the duct 8, plunger 62 and ports 62. From the chamber 59 the lower grade of fuel discharges the same as described for the gasoline. 80

To enable the engine to deliver higher speed or power, the valve 37 will be opened to admit more air into the air admission chamber 32 and the throttle valve 80 will be opened to the desired amount so as to increase the degree of vacuum in the mixing chamber 7. The increased degree of vacuum raises the air valve 44 so as to admit a greater flow of air from the chamber 31 through the ports 51 to the interior of the 85 air valve. This raising of the air valve also causes raising of the rod 65 to cause a greater degree of opening of the valve 60 thus allowing fuel to flow from the duct 8 into the bore of the plunger 62, thence 90 through the ports 63 to the bore of the stem 59, thence through the ports 78 into the internal nozzle member 71, thence through the ports 77 to the bores of the external nozzle members 69, 73, thence through the 95 nozzle orifices 74, 76 into the annular space between the external nozzle members and air nozzle 54. It is clear that the air admitted through the ports 55 sweeps over the peripheral faces of the nozzle members 69, 73 so as to spread the fuel issuing from the nozzle orifices over the peripheral faces of the external nozzle members in order that the column of air will readily 100 absorb the fuel and thus break it up 105 into exceedingly small particles to insure the making of an intimate mixture of the fuel and air. The carburetor may be adjusted for the desired proportions of fuel and air by turning the nut 67 so as to adjust 110 the beginning of opening movement of the valve 60 relative to the degree of opening of the air valve 44. If the throttle valve 80 be opened suddenly to a relatively great degree the air valve 44 and fuel valve 60 will not 115 move immediately to corresponding open position since the fluid above the plunger 62 retards upward movement of said plunger. The plunger 62 does not fit snugly in the chamber 49, there being sufficient space between the plunger and chamber 49 to allow 120 the fuel in the chamber 49 to pass slowly from above the plunger to beneath it. If, however, the throttle valve 80 be closed suddenly the air valve 44 and fuel valve 60 will 125 130

function to quickly reduce the supply of air and fuel because the plunger 62 is not materially retarded in its downward movement, owing to the provision of means to quickly relieve the pressure beneath the plunger. To provide for the plunger 62 falling quickly, the plunger is provided with a valve chamber 82 communicating with the space above the plunger through a port 83 10 and communicating with the space beneath the plunger through a port 84. The port 84 is controlled by a ball valve 85 in the valve chamber 82. Thus when the plunger is drawn upward the valve 85 remains closed 15 so that the fuel above the plunger offers resistance to the upward movement of the plunger. When the plunger falls the pressure of the fluid below the plunger operates to raise the ball valve 85 so that the fluid beneath the plunger can rapidly escape through the port 84 into the valve chamber 82, thence through the port 83 into the space 20 above the plunger.

When the throttle is opened but slightly 25 and the air valve 44 is closed upon the seat 53, the air will flow from the air valve only through the ports 55 into the air nozzle 54 so that all of the air will sweep through the air nozzle in close proximity to the nozzle orifices 74, 76 and spread the fuel in a thin 30 film over the upwardly and inwardly slanting faces of the nozzle members 69, 73 and thus provide for quick vaporization of the fuel. When the throttle is opened wider to 35 cause lifting of the air valve 44 the air not only flows from the air valve into the air nozzle, as before, but also flows as an auxiliary supply from the air valve through the annular gap then existing between the air 40 valve seat 53 and air nozzle shoulder 52, so that the mixture is decreased in richness or, in other words, the ratio of fuel to air is decreased though the volumes of both fuel and air are increased. Thus I have provided 45 means to discharge an initial supply of air close to the nozzle when the air valve is in one position and to discharge an auxiliary supply of air above the nozzle when the valve is in another position. Also it is clear 50 that the one air valve 44 controls both the initial and auxiliary supplies of air to the mixing chamber.

In order to "prime" the carburetor, that is to say, to cause a flow of fuel from the nozzle orifices 74, 76, the base 6 is provided with an orifice 86 in which is positioned a priming pin 87 that is in alignment with the lower edge of the air valve 44 so that an upward push on the pin 87 will raise the air valve 60 and consequently cause opening movement of the fuel valve 60. It is understood that to effect such priming the tank, not shown, for supplying the fuel to the carburetor will be positioned above the level of the nozzle

orifices 74, 76 or that pressure will be produced on said fuel by other suitable means to cause the fuel to discharge from the nozzle orifices when the valve 60 is opened and the valve 10 is turned to effect communication between the ducts 9 and 11. 70

It is noted that the abutment 24 may be adjusted sufficiently high on the stem 22 to cause the fuel to rise to or above the level of the nozzle orifices when the valve 60 is open and the valve 10 is turned to effect communication between the chamber 3 and duct 9. 75

It is to be noted that the nut 67 and collar 68 constitute a loose connection between the air valve 44 and valve stem 59, 65 since the collar 68 is shiftable in the perforation 88 80 of the bridge.

I claim:

1. In a carburetor, the combination of a tubular member closed at its lower end and provided with a port, a tubular air valve 85 slidably fitting in the tubular member for controlling the air admitted by the port and having a shoulder, a nozzle inside of the valve, an air tube surrounding the nozzle and having its upper portion spaced therefrom and having a port communicating with the interior of the valve and provided above the level of its port with a seat for engagement with the shoulder, and a valve to control the flow of fuel through the nozzle, said fuel valve being operatively connected with the air valve. 90 95

2. In a carburetor, the combination of a fuel chamber, a nozzle mounted on the upper end of the fuel chamber, a post extending 100 into the fuel chamber and having a fuel duct, a valve to control the fuel duct and projecting into the nozzle, and a chambered stem for the valve having a port communicating with the fuel chamber and another 105 port communicating with the interior of the nozzle.

3. In a carburetor, the combination of a fuel chamber, a nozzle mounted on the upper end of the fuel chamber, a post extending 110 into the fuel chamber and having a fuel duct, a valve to control the fuel duct and projecting into the nozzle, a chambered stem for the valve having a port communicating with the fuel chamber and another port communicating with the interior of the nozzle, and a hollow plunger in the fuel chamber surrounding the post and connected with the valve, the plunger being provided with means to allow the passage of fuel therethrough on 115 its down stroke and to prevent the passage of fuel therethrough on its up stroke. 120

Signed at Los Angeles, California, this 8th day of April, 1919.
